UNITED STATES PATENT OFFICE.

ALLAN B. FIELD, OF PITTSBURGH, PENNSYLVANIA, ASSIGNOR TO WESTINGHOUSE ELECTRIC AND MANUFACTURING COMPANY, A CORPORATION OF PENNSYLVANIA.

COIL-SUPPORT.

1,238,280.

Specification of Letters Patent. Patented Aug. 28, 1917.

Application filed August 2, 1913. Serial No. 782,565.

To all whom it may concern:

Be it known that I, ALLAN B. FIELD, a subject of the King of England, and a resident of Pittsburgh, in the county of Allegheny and State of Pennsylvania, have invented a new and useful Improvement in Coil-Supports, of which the following is a specification.

My invention relates to dynamo-electric machines and it has special reference to means for supporting and spacing the portions of coils that overhang the cores of such machines.

The object of my invention is to provide an effective, reliable and simple means of the above-indicated character.

Heretofore, the several intercrossing layers of coils comprising the overhanging portions have been supported and spaced by means of a plurality of devices severally comprising a plurality of blocks of insulating material disposed on the exterior of said layers and a plurality of bolts extending through said blocks and severally between said coils. The blocks were bolted to metal brackets attached to the core. Displacement of the coils was prevented chiefly by friction, necessitating a pressure which tended to injure the insulating material. In case of a short-circuit of the machine, the layers of winding tend to shear on one another, and the above described means of supporting the coils has been found unsatisfactory, particularly in large machines, in such an extremity, chiefly by reason of the small bearing surface of the bolts upon the coils.

According to my invention, I provide a supporting and spacing member adapted for disposal intermediate the layers of coils and having a plurality of projecting ribs oppositely inclined on opposite sides of the said member for engaging and spacing the several coils in the said layers. The old means, hereinbefore described, of clamping down the coils and attaching the spacing members to the machine core, or any other suitable means, may be employed. It will be understood that the coils are prevented from relative motion by reason of the wedging action of my device, which simultaneously engages the intercrossing layers, and thus stiffens the winding considerably, irrespective of the clamping means, which,

moreover, does not require the application of excessive pressure.

It will be also understood that the shearing tendency of the coil layers in case of a short-circuit is successfully overcome by the relatively large bearing surface on the coils of the separating member employed in my invention.

In the accompanying drawings, Figure 1 is a view in longitudinal section on the line L—L of Fig. 4; Fig. 2 is a view in top plan and Fig. 3 is a view in side elevation, partially in section, of the separator; Fig. 4 is a view in plan development, with parts omitted for clearness, of a portion of a dynamo-electric machine embodying my invention; Fig. 5 is a view, partially in section on the line V—V of Fig. 4, and showing the disposition of coils.

Referring to the drawings, a dynamo-electric machine 1 is provided with a core 2, an end-plate 2^a, and a plurality of coils 3 disposed in core slots and severally having portions 4 which overhang the core and constitute a substantially frusto-conical structure that comprises outer and inner intercrossing layers 5 and 6, respectively. A plurality of my coil-supporting devices 7 are attached at intervals to the overhanging portions, as hereinafter described.

The devices 7 severally comprise a coil-separator 8 disposed intermediate the coil layers 5 and 6, a plurality of clamping bars 9 disposed exterior to the said layers, a plurality of plates 10 disposed upon the outer sides of the bars 9, and a plurality of bolts 11 for holding the entire device 7 in position.

The coil separator 8 comprises a bar 12 provided with a plurality of spaced ribs 13 and 14 located on opposite sides thereof and oppositely inclined for engaging and spacing the several coils 3 in the outer layer 5 and the inner layer 6, respectively. A plurality of bolt-holes 15 severally extend at intervals through the ribs 13 and 14 and the bar 12, and a relatively larger hole 15^a is provided in one end of said bar. The clamping bars 9 may consist of any suitable insulating material, and the exterior plates 10 are preferably of sheet metal, for mechanical reasons. The bolts 11 extend through the plates 10, the bars 9 and the

bolt-holes 15 in the separator 8, and a plurality of nuts 16 are disposed upon one end of each of said bolts for permitting an application of pressure on the coil-supporting device 7.

5 A plurality of brackets 17 are provided at intervals on the core 2 or on the end plate 2^a for attachment, by means of a plurality of bolts 18, preferably to every alternate 10 coil-supporting device 7, although any other arrangement may be employed. The brackets 17 are generally in the form of right-angled triangles, the hypotenuses of which coincide with elements of the frusto-conical structure formed by the end-turns. In Fig. 15 5 my device 7 is shown without any attachment to the machine 1.

The necessity for effectively insulating the coils 3 from the conducting portions of the 20 coil-supports 7 will be understood. As a means of accomplishing the desired result, extra insulating material may be provided at all surfaces of contact between said coils and said coil-supports; and the end bolts 11, 25 that are employed for attaching the said supports to the brackets 17, may be insulated from the separator 12 by disposing a suitable body of cement, or the like, around said bolts within the enlarged holes 15^a. It is understood that the manner of insulating the 30 devices 7 from the coils 3 is not essential to my invention, and that any suitable means may be employed.

I do not desire to be restricted to the specific structures and details herein set forth, 35 but desire that only such limitations shall be imposed as are indicated in the appended claims.

I claim as my invention:

40 1. In a dynamo-electric machine, the combination with a core and a plurality of coils disposed thereon and having portions that overhang said core and comprise a plurality of intercrossing layers, of a plurality of members each adapted for spacing the layers and the coils in different layers.

2. In a dynamo-electric machine, the combination with a core and a plurality of coils disposed thereon and having portions that 50 overhang said core and comprise a plurality of intercrossing layers, of a unitary member for spacing the layers and the coils in different layers at a point where said layers intercross.

55 3. A coil-separating device for use with overhanging and intercrossing portions of coils on dynamo-electric machines comprising a base member and a plurality of ribs oppositely inclined to the axes of said member on opposite sides of said member for engaging and spacing the several coils in said portions.

4. In a dynamo-electric machine, the combination with a core and a plurality of coils disposed thereon and having portions that 60

overhang said core and comprise a plurality of intercrossing layers of a plurality of members each adapted for spacing and supporting the coils in different layers.

5. In a dynamo-electric machine, the combination with a core and a plurality of coils disposed thereon and having portions that 70 overhang said core and comprise a plurality of intercrossing layers, of a unitary member adapted for spacing and supporting the 75 coils in different layers at a point where said layers intercross.

6. In a dynamo-electric machine, the combination with a core and a plurality of coils disposed thereon and having portions that 80 overhang said core and comprise a plurality of intercrossing layers, of a plurality of supporting members for said overhanging portions each provided with projections for spacing the coils in different layers when 85 said layers intercross.

7. In a dynamo-electric machine, the combination with a core and a plurality of coils disposed thereon and having portions that 90 overhang said core and comprise a plurality of intercrossing layers, of a plurality of supporting members for said overhanging portions each provided with ribs on opposite sides thereof for spacing the coils in different 95 layers.

8. In a dynamo-electric machine, the combination with a core and a plurality of coils disposed thereon and having portions that 100 overhang said core and comprise a plurality of intercrossing layers, of a plurality of supporting members for said overhanging portions severally provided with oppositely-inclined ribs on opposite sides thereof for spacing the coils in said layers.

9. In a dynamo-electric machine, the combination with a core and a plurality of coils disposed thereon and having portions that 105 overhang said core and comprise a plurality of intercrossing layers, of a plurality of supporting bars for said overhanging portions severally provided with oppositely-inclined integral ribs on opposite sides thereof for engaging and spacing the several 110 coils in said intercrossing layers, and means 115 for attaching said bars to said core.

10. In a dynamo-electric machine, the combination with a core and a plurality of coils disposed thereon and having portions that 120 overhang said core and comprise a plurality of intercrossing layers, of a plurality of supporting bars adapted for disposal intermediate said intercrossing layers and provided with oppositely-inclined integral ribs on opposite sides for engaging and spacing the several coils in said layers, and means 125 for clamping said overhanging portions to said bars.

11. In a dynamo-electric machine, the combination with a core and a plurality of coils disposed thereon and having portions that 130

that overhang said core and comprise a plurality of intercrossing layers, of a plurality of supporting bars adapted for disposal intermediate said intercrossing layers and provided with oppositely inclined integral ribs on opposite sides for engaging and spacing the several coils in said layers, means for clamping said overhanging portions to said bars, and means for severally attaching said bars to said core.

12. In a dynamo-electric machine, the combination with a core and a plurality of coils disposed thereon and having portions that overhang said core and comprise a plurality of intercrossing layers, of a plurality of supporting bars adapted for disposal intermediate said intercrossing layers and provided with oppositely-inclined integral ribs on opposite sides for engaging and spacing the several coils in said layers, insulating material disposed exterior to said layers, a plurality of bolts severally extending through said material and said ribs for clamping said coils thereto, and a plurality of bolts severally extending through said material and said bars for attaching the same to said core.

13. In a dynamo-electric machine, the combination with a core and a plurality of coils disposed thereon and having projecting portions that are arranged to form a frusto-conical structure, of an end-plate for said machine, a plurality of radially disposed supporting brackets engaging ele-

ments of said structure and attached to said end-plates, and a plurality of coil-separating devices severally comprising a base member, a plurality of projections for spacing the several coils in said portions, and means for attaching said member to said core.

14. In a dynamo-electric machine, the combination with a core and a plurality of coils disposed thereon and having projecting portions that are arranged to form a frusto-conical structure, of an end-plate for said machine, a plurality of radially disposed triangular supporting brackets for said coils attached to said end-plates, and a plurality of coil-separating devices severally comprising a base member, a plurality of ribs on opposite sides of said member for engaging and spacing the several coils in said portions and means for attaching said member to said core.

15. A coil-separating device comprising a base portion and a plurality of ribs equally and oppositely inclined to the axes of said base portion and on opposite sides of said base portion.

In testimony whereof, I have hereunto subscribed my name this 26th day of July, 1913.
